UNITED STATES PATENT OFFICE.

GEORGE E. GRIFFIN, OF NEW YORK, N. Y., ASSIGNOR TO UNDERWOOD TYPEWRITER COMPANY, OF NEW YORK, N. Y., A CORPORATION OF DELAWARE.

TYPE-WRITING MACHINE.

1,117,664.

Specification of Letters Patent. Patented Nov. 17, 1914.

Application filed November 14, 1910. Serial No. 592,214.

To all whom it may concern:

Be it known that I, GEORGE E. GRIFFIN, a citizen of the United States, residing in the borough of Brooklyn, city of New York, in the county of Kings and State of New York, have invented certain new and useful Improvements in Type-Writing Machines, of which the following is a specification.

The present invention relates to an improved tabulating mechanism for typewriting machines.

The invention relates in part to tabulating mechanism, known as a column "skipper" or "jumper", comprising a set of stops carried by a rack on the carriage and set to correspond in number and position to the columns of the tabulation to be written; and key-controlled means to release the carriage and coöperating with the column stops on the carriage to arrest the carriage at a selected column position, which setting may involve the skipping of one or more columns or column stops before the carriage is arrested.

25 The invention also provides, in combination with the column-selecting mechanism, a decimal tabulator comprising a set of stops on the carriage; and key-controlled stops co-operating with the carriage stops to arrest the carriage at a desired decimal position in the column to which the carriage has been brought by the column-selecting mechanism.

I provide a tabulating mechanism, the carriage stops and key operated parts of which 35 may be used, either as a column selecting apparatus, by means of which the carriage may be skipped to a desired column; or as a decimal stop mechanism by means of which the carriage may be jumped to a desired "decimal" position in a column. In the structure hereinafter described, the carriage stops are of two kinds, one or the other of which may be exclusively employed in connection with: the key operated means according as to 40 whether the mechanism is to be used as a column "skipper" or selector, or as a decimal tabulator. Also the column-selecting and the decimal-selecting features may be combined, and both kinds of carriage stops 45 may be employed at the same time and be governed from a single set of keys. Each key may control some one column-selecting stop and also some one decimal tabulator stop, said key having the same movement, 50 both in direction and degree for both purposes. The keys each having a marking from

"1", "2", "3", etc., to indicate the column to be selected by the key when the key is operated as a column selecting key; and the keys have also each a marking to indicate the decimal stop controlled from the key when the key is used as a decimal selecting key. A key may be operated to bring the carriage to a selected column position, and the same or another of the keys, according to the decimal 65 desired, may then be operated to jump the carriage from the selected column position to the desired decimal position in that column.

Another feature of the invention is to 70 provide a mechanism in which the column-selecting key operated parts are relieved of the weight of the stop device which coöperates with a stop on the carriage in arresting the latter. The column selecting keys set 75 certain devices so that the same, when set, may be struck and actuated by the carriage, and when so actuated by the carriage may operate the movable stop which is to arrest the carriage at the selected column.

Another feature of the invention is a 80 universal or single stop controlled from each of the column selecting keys on the carriage and adapted to be moved into engagement with the carriage to arrest the latter in 85 the different column positions, depending upon which column key is operated.

The first column stop key may be operated to give the carriage a column to column movement where no column skipping is desired, or in which any other key representing a column already passed may be repeatedly used for column to column advance of the carriage during the rest of the line.

Column-selecting stops adjustably mounted 95 on the carriage rack comprise tappets of different lengths arranged to project progressively to different distances from the rack. Interponents, which may be in the form of pivoted arms or pawls, are mounted 100 on a movable support, the interponents arranged in a series which extends at right angles to the carriage rack and are projectable selectively by means of a series of key-actuated plungers into the path of said tappets. 105 When a selected interponent is projected by depressing the corresponding key, the carriage is released and runs forward until the tappet corresponding to the projected interponent strikes the latter and swings its 110 support to project a counter-stop into the path of said tappet, and thereby brings the

carriage to rest at the column position corresponding to the actuated key. In addition to the column-selecting stops on the carriage rack, decimal stops may be placed on the rack and may be intercepted by the said plungers. Thus the carriage may be brought to any selected column position by actuating the corresponding key of the series, and then brought to the desired decimal position in the column by actuating the key corresponding to the desired decimal position.

Other objects and features of the invention will presently appear.

In the accompanying drawings, Figure 1 is a view in side elevation, partly cross sectional, of the mechanism of the present invention and allied parts. Fig. 2 is a view in front elevation of the parts shown in Fig. 1, the carriage frame and key levers being omitted. Fig. 3 is a top plan view of the assembled stop rack, column stops, and co-operating plunger mechanism. Fig. 4 is a detail view showing one of the decimal stops in position on the rack and in engagement with one of the stop plungers. Fig. 5 is a detail view showing one of the column stops in position on the rack. Fig. 6 is a perspective view of the mechanism shown in Fig. 1. Fig. 7 is a view similar to Fig. 6, the parts being shown in slightly different position. Fig. 8 is a detail perspective view showing the stop plungers and means operated thereby to arrest the carriage by engagement with the column stops, the parts having been set. Fig. 9 is a view in front elevation of the parts shown in Fig. 1, a key having been operated to release the carriage and set a stop plunger. Fig. 10 is a detail perspective view similar to Fig. 8 except the parts are in normal position and the carriage rack is omitted. Fig. 11 is a detail perspective view showing the connection of the universal stop to the pawl carrying frame. Fig. 12 is a detail view in front elevation showing the stop setting mechanism at the time the same is engaged by one of the column stops.

The power-driven carriage 1, which is partly shown in Fig. 1, and which carries the platen and other parts (not shown), is mounted in a well known manner to have longitudinal movement on a rail 2, supported in the main frame 3 of the machine. The carriage is driven from the usual spring drum 3a shown in dotted lines (Fig. 1), and its letter feed movement is controlled by an escapement mechanism comprising a pinion 4 (see Fig. 2) which engages the escapement rack 5 on the carriage. The escapement rack is supported from the carriage by means of arms 6 pivoted at 7, one to each end of the carriage frame. The rack 5 rides upon a roller 8, and by means of the latter may be lifted out of engage-

ment with the pinion 4. One of the arms 6 is extended beyond the pivot 7 to carry a release key (not shown) for rocking the arm to lift the rack out of engagement with the pinion, so that the carriage may be moved free of the control of the escapement mechanism.

The present machine is especially adapted for tabulating work, and to this end comprises: a mechanism for releasing the carriage from the escapement wheel so that the carriage may be thrown from column to column by the drum spring; a system of stops adjustably set on the carriage of the machine according to the column positions in the tabulation; and a system of key controlled stop plungers co-operating with the fixed adjustable stops on the carriage, to select and stop the carriage at a desired column or decimal position in a column when the carriage is released from the escapement wheel.

The column stops are shown at 10, engaging the teeth of a rack 11 which is attached by means of brackets 12 (see Fig. 9) to the carriage frame, so as to be movable with the carriage. The rack 11 has an upper and lower toothed face, and the stops 10 are shaped so as to engage the rack above and below, and to fit between the teeth of the rack so as to be held by the latter against displacement. To position the stops, the same are forced onto the rack from the rear. The column stops 10, (see Fig. 3) are shown as tappets of different lengths, the first tappet being shown as the shortest, and the length of the tappets progressively increasing from left to right.

For engaging any particular stop or tappet to arrest the carriage at the desired column, there is mounted in the tabulator frame 13 secured to the main frame, a series of vertically movable plungers 14, each of which at its lower end engages with one of a number of keys 15 pivoted at 16 to the main frame and comprising a finger-piece 17 in the keyboard. The finger-pieces 17 are each marked from No. 1 to No. 10, from left to right. The plungers 14, near their upper ends, have each a forwardly extending arm 18 (see Figs. 3, 6 and 10), and each of the arms 18, except that of the first column plunger, is turned to have an offset portion 19 terminating in a tooth 20. The arms 18 and offset portions 19 are shown as of progressively increased length so that the plunger teeth 20 (see Figs. 3 and 10) may be alined perpendicularly to the line of movement of the rack 11. The distance of the teeth 20 from the rack 11, therefore, increases for each succeeding column plunger, and this increase in distance corresponds to the increase in length of the column stops 10.

The column stop representing the first column is of sufficient length to extend into

the plane of the tooth 20 of the first plunger, the stop of the second column is of sufficient length to extend into the plane of the tooth 20 of the second plunger, etc.

- 5 Each of the plunger teeth 20 forms a column-selecting device to coöperate with one of a series of spring pawls or interponents 21, so that when any particular plunger is thrown up by its appropriate key 15, it engages its spring pawl 21 and forces the latter into the path of all the column stops 10 which are of sufficient length to reach from the rack to the plane of the pawl so lifted. The interponent 21 thus operated is therefore 15 presently engaged by a column stop 10 and acts to arrest the carriage.

The pawls 21 are mounted to swing independently of one another on a rod 22 as a pivot. The rod 22 is carried by a plate 23 on 20 a bracket 25 secured to the tabulator frame 13. There is attached to each pawl 21 one end of a coil spring 26, the other end of which is attached to the bracket 25, whereby each of the pawls is held down against its 25 respective plunger tooth 20 and is returned to normal position after being operated.

The plate 23, on which the pawls are pivoted, is not rigid with the bracket 25, but is carried on or formed with a sleeve 27 supported on a pin 24 in the bracket, so that the plate 23 with the pawls may swing bodily on the pin 24 as a pivot when a stop 10 driven by the carriage strikes any pawl. The sleeve 27 also carries an arm 28, the end 35 of which engages in a hole 29 in a universal plunger 30.

The plunger 30 is mounted to have vertical movement in the tabulator frame 13, and when lifted, its upper end enters the path of 40 movement of the same stop 10, which by means of the pawl has thus moved the plunger 30. When, therefore, upon operation of one of the plungers 14, a pawl 21 is lifted and is struck by a column stop 10, the pawl 45 so struck is forced back, and swings the plate 23 on its pivot 24, causing the arm 28 and the universal plunger 30 to be lifted in front of the stop. When this stop 10 has moved with the pawl a sufficient distance, it 50 strikes the plunger 30 (see Fig. 12) which it itself has lifted, and thus arrests the movement of the carriage. The plunger 30 therefore acts to stop the carriage no matter what plunger 14 is operated. It will be noted 55 that the plunger 30 is not moved by the keys 15, but is operated by the force of the moving carriage. As the burden of stopping the carriage therefore does not fall upon the key-operated pawls 21, these latter may be 60 light and small, and are not subject to injury or appreciable wear. The plunger 30 on the other hand, not being operated from the keys, may be as heavy and substantial as desired.

65 The universal plunger 30 moves in a guide

31 on the tabulator frame. It is held normally depressed, and is returned to normal position by a coil spring 32. The particular pawl 21 which was lifted, is swung down by its spring 26 as soon as the column key is released, the ends of the pawls 21 being so shaped as to be readily disengaged from the column stops. When the operated pawl is thus released, the spring 32 returns the universal plunger, the latter, by engagement with the arm 28, returning the plate 23 and the pawls 21 to the position from which they were forced by the impact of the carriage stop.

Simultaneously with the operation of any 80 plunger 14, the carriage is released from the escapement rack in order that it may be thrown by the spring drum 3a to the column position determined by the particular plunger operated. The means for releasing the 85 carriage is well known, and is as follows:

Each plunger has a shoulder or tooth 34 which projects below a universal bar 35 carried on arms 36 fast to a rock shaft 37. Also fast to shaft 37 is an arm 38 connected 90 by a link 39 to a lever 40 pivoted at 41 to the main frame. On the end of the lever 41 is a bearing pin 42 for the roller 8 on which the carriage escapement rack 5 rests. When therefore any plunger 14 is lifted by 95 its key lever 15 the tooth or arm 34 on that plunger engages the universal bar 35 to rock the shaft 37, and through arm 38, link 39, and lever 40, to lift the roller 8 with the rack, so as to disengage the latter from the 100 escapement pinion 4. A stop bar 43 determines both the upward and downward movement of any plunger 14 which may be operated. A coil spring 44 on the rock shaft 37 returns the latter, and all the parts connected thereto, to normal position when the key 15 is released. The spring 44, acting through the universal bar 35, may serve to return the plungers to normal position, and the plungers on returning to normal position will return the keys to normal position. When the key is released and the spring 44 acts, the rack 5 falls back again into engagement with the escapement pinion, and the machine is ready for letter feed at the new 115 column.

In the operation of the invention as above described, the keys 15 act as column stop keys, any one of which may be depressed, and the carriage thereby released and caused 120 to jump to the column position controlled by the particular key operated. If, for instance, the key No. 5 is depressed, the No. 5 plunger 14 and the No. 5 pawl 21 will be operated. The No. 5 pawl 21 is so far from the rack 11 125 that the first four column stops 10 cannot reach it, and consequently pass by it, as the carriage is impelled to the left by the drum spring. The No. 5 stop 10, however, is long enough to reach the No. 5 pawl 21, and on 130

striking it causes the universal plunger 30 to be thrown up to intercept the No. 5 column stop 10 and thereby stop the carriage. The No. 5 key 15 is then released to bring the carriage again under the control of the escapement mechanism, and the parts being returned to normal position by their several springs, the letters or other characters in the column are written in the usual manner. If thereafter, it is desired to jump from column No. 5 to column No. 7, for instance, the column No. 7 key is depressed. If, however, column No. 6 is the next column desired, the column No. 6 key may be depressed, or any of the keys of the previous columns may be depressed in lieu thereof, because the column No. 6 stop 10, being long enough to engage the column No. 6 pawl 21, must necessarily engage any operated pawl 21 which is nearer the rack 11 than the No. 6 pawl. It follows therefore that where no column is to be skipped the column No. 1 key 15 may be used for every column advance of the carriage throughout the line; or any other key may be repeatedly used which represents a column already reached by the carriage.

The plungers 14 have been described in connection with the column stops 10 and with certain other parts going to make up a column skipping mechanism. The plungers 14 are, however, adapted to subserve another and different purpose. They are adapted to serve as the "decimal" stop plungers or counter-stops of a decimal tabulator. When the machine is to be used in the latter capacity, the column stops 10 may be discarded, and a set of stops 45, such as shown in Fig. 4, employed instead of the stops 10. The stops 45 engage the rack 11 in the same manner as the stops 10. The stops 45 are, however, all of the same length and do not extend beyond the rack 11 in such manner as to engage any of the pawls 21. They project somewhat below the rack, so that whenever a plunger 14 is elevated, the upper end 46 of the plunger is projected into the path of the stops 45 to form a counter-stop for said stops. When a plunger 14 is thus operated, and the carriage is released and moves to the left with the stops 45, the first stop 45, to reach the bank of plunger stops 14, engages that plunger which has been elevated, and so arrests the carriage. The plungers 14 are spaced one from the other the regular letter feed distance, so that each plunger 14 may represent a decimal position in the column. The plunger 14 to the extreme left represents the "decimal point" position and those to the right of it, the position for the unit, the ten, the hundred etc. According, therefore, to which of the keys 15 is operated, the carriage will be arrested by a stop 45 at some one selected decimal position in the next column. The key ends 17, in addition to having a "column" mark-

ing for use in connection with the column stops 10, have also a "decimal" marking (see Fig. 6) for use in connection with the stops 45. When only the stops 10 are used, the ends 46 of the plungers 14 have no function, and in order that these ends 46 may not engage the stops 10 and thus prevent column skipping, the stops 10 are cut away as at 48 to form openings through which the end 46 of the elevated plunger 14 may freely pass during the movement of the carriage. When only the stops 45 are employed, the plunger arms 18 and pawls 21 have no function. It is true that every time a plunger is operated, there is also operated a pawl 21. The stops 45 do not however reach the pawl so operated, and consequently the universal plunger 30 is not lifted at such times.

The mechanism has been described as a "column skipper" and as a "decimal tabulator". It may be operated to combine both of these functions. In other words, the carriage may not only be jumped to any predetermined column position by means of the key having the suitable column number, but it may thereafter be jumped from the said predetermined column position to any desired decimal position in the column by means of the key with the proper decimal number. In such use of the machine, both forms of stops are used. The markings on the scale 50 (see Fig. 3) are ten to the inch to represent the ten decimal positions of a column. With due reference to this scale, the column stop 10 for each column with which a decimal tabulator stop 45 is also used, should be positioned a sufficient number of points to the left of the stop 45 for that column, to permit the stop 10 to engage its pawl and throw the universal plunger 30 before the stop 45 reaches the position of the extreme right hand plunger 14. The stop 10 will therefore arrest the carriage with the stop 45 in such position that thereafter any of the plungers may be selected to coöperate with the stop 45 in determining the decimal stopping position of the carriage for that column. In Fig. 3 the universal plunger 30 is shown in alinement with the decimal point plunger stop terminal 46, that is to say, nine points to the left of the extreme right hand plunger 14. A stop 45 used in conjunction with a stop 10 should therefore be positioned at least nine points to the right of the latter stop. Of course, where the matter to be written is such that the higher decimal positions are not needed, then the distance between the stops 10 and 45 may be accordingly reduced.

When the mechanism is used as a combined "column-skipper" and "decimal tabulator", the decimal stops 45 are only used at certain of the columns for which the column-selecting stops 10 are set, as for example, one or two of the columns at the

right-hand side of the work-sheet. As the preceding column stops 10 therefore have no associated decimal stops 45, they may perform their normal functions of column-selecting devices. In other words, when the two sets of stops are combined, the keys 15 may be selectively operated to bring the carriage by a single movement to any columnar position to the left of or including 10 the first column with which a decimal stop is used. The same or a second key 15 may then be operated to bring the carriage to the required decimal position in the column. Obviously the decimal stops 45 might also 15 be used for columns at the right or intermediate positions on the work-sheet without interfering with the normal action of the stops 10 as column-selecting devices for other columns where the stops 45 are 20 omitted.

This invention is of particular advantage in machines with carriages taking a very wide work-sheet. On such sheets, such as 25 certain types of insurance reports, it is sometimes desirable to group ordinary description in certain columns near the left of the work-sheet, and valuations in one or two at the right of the sheet. These valuations should be so positioned that they may be 30 footed, and they are most easily so positioned by means of a decimal tabulator. For such work therefore, a column selector is required over the first part of the run of 35 the typewriter carriage, while a decimal tabulator is required over the end portion of the travel of the carriage. The present invention meets such a requirement with a single set of keys.

Where the two stops are used, two key 40 operations are seen to be sometimes necessary, the first by a key to select the column, and the second by a key to select the decimal position in the column. One operation of a column key will not however suffice to cause the carriage to skip a column 45 for which there is a stop 45 on the rack 11, because although the stop 10 of the column to be skipped will, by virtue of the opening 50 pass the end 46 of the plunger operated, yet the stop 45 of the column to be skipped 55 will not pass the end 46 of the operated plunger, but will engage that plunger and stop the carriage. Upon a second operation of the selected column stop key, the 60 carriage will pass to the next column. If this next column is the selected column, the carriage will be arrested there by the universal plunger 30; or if not the selected column, then by the stop 45 of that column, in which latter event the selected column 65 key is again operated, until in this manner the carriage is finally brought to the proper column.

The stops 10 and 45 have shoulders 51 behind which the scale plate 50 rests (see Fig.

1), in such manner as to lock the stops on the rack 11. The scale is carried on arms 52 pivoted at 53 to brackets 54 carried by the rack 11, so that the scale may be swung up to permit of the positioning of the stops. 70

The structure herein shown and described is susceptible of a variety of modifications within the scope of the invention. The form of the stops, the arrangement of the stops, and the stop-operating mechanism 75 may all be modified by one skilled in the art to meet any particular requirements. The most important feature of the invention is the adaptability of the mechanism to both column skipping and decimal tabulating 80 purposes.

Having thus described my invention, I claim:

1. In a typewriting machine, the combination of a power-driven letter feeding carriage, carriage releasing means to permit the carriage to be thrown from one column position to another, a set of adjustable column selecting stops for the carriage having varying horizontal extensions, a series of trips 85 arranged to be selectively moved into position to be struck by said extensions, an arresting member swung by said trips, a set of adjustable stops for selecting decimal positions for the carriage in the selected 90 columns, and key-operated plungers moving vertically to selectively set said trips to cooperate with said column-selecting stops to arrest the carriage in the selected positions. 95

2. In a typewriting machine, the combination of a power-driven letter feeding carriage, carriage-releasing means to permit the carriage to be thrown from one column position to another, a set of adjustable column selecting stops for the carriage having varying 100 horizontal extensions, a series of trips arranged to be selectively moved into position to be struck by said extensions, a set of adjustable stops for selecting decimal positions for the carriage in the selected columns, 105 means moved vertically, by said trips to cooperate with the column selecting stops to arrest the carriage at the selected columns, and other means co-operating with the decimal stops to arrest the carriage at the selected 110 decimal position in the selected column. 115

3. In a typewriting machine, the combination of a power-driven letter feeding carriage, carriage releasing means to permit the carriage to be thrown from one column position to another, a set of adjustable column selecting stops for the carriage, and a set of 120 adjustable stops for selecting decimal positions for the carriage in the selected columns, means co-operating with the column selecting 125 stops to arrest the carriage at the selected columns, and other means co-operating with the decimal stops to arrest the carriage at the selected decimal position in the selected column, and a set of keys each of which con- 130

trols both the said column selecting and the said decimal selecting means.

4. In a typewriting machine, the combination of a power-driven letter feeding carriage, carriage releasing means to permit the carriage to be thrown from one column position to another, a set of adjustable column selecting stops for the carriage, a set of adjustable stops for selecting decimal positions for the carriage in the selected columns, means coöperating with the column selecting stops to arrest the carriage at the selected columns, and other means coöperating with the decimal stops to arrest the carriage at the selected decimal position in the selected column, a set of keys each of which controls both the said column selecting and the said decimal selecting means, said keys each having a character to indicate the column stop controlled thereby, and another character to indicate the decimal stop controlled thereby.

5. In a typewriting machine, the combination of a power-driven letter feeding carriage, carriage releasing means to permit the carriage to be thrown from one column position to another, a set of adjustable column selecting stops for the carriage, and a set of adjustable stops for selecting decimal positions for the carriage in the selected columns, means coöperating with the column selecting stops to arrest the carriage at the selected column, and other means coöperating with the decimal stops to arrest the carriage at the selected decimal position in the selected column, and a set of keys and means connecting each of said keys to said selecting means so that it may first be operated to select a column and may thereafter again be operated to release and then arrest the carriage at some one decimal position in the selected column.

6. In a typewriting machine, the combination of a power driven letter feeding carriage, carriage releasing means to permit the carriage to be thrown from one column position to another, a first set of stops adjustable on the carriage, and extending varying distances horizontally for arresting the carriage in predetermined column positions, a second set of stops adjustable on the carriage for arresting the carriage in selected decimal positions in the columns, a first class of vertically working key controlled means coöperating with the first set of stops to arrest the carriage in selected column positions, and a second class of key controlled means coöperating with the second set of stops to arrest the carriage in selected decimal positions in the selected columns.

7. In a typewriting machine, the combination of a power-driven letter feeding carriage, carriage releasing means to permit the carriage to be thrown from one column position to another, a first set of

stops adjustable on the carriage for arresting the carriage in predetermined column positions, a second set of stops adjustable on the carriage for arresting the carriage in selected decimal positions in the columns, a first class of key controlled means coöperating with the first set of stops to arrest the carriage in selected column positions, a second class of key controlled means coöperating with the second set of stops to arrest the carriage in selected column positions in the selected columns, and a set of keys each of which simultaneously actuates a stop coöperating means of each of said classes.

8. In a typewriting machine, the combination of a power-driven letter feeding carriage, carriage releasing means to permit the carriage to be thrown from one column position to another, a first set of stops adjustable on the carriage for arresting the carriage in selected decimal positions in the columns, a first class of key controlled means coöperating with the first set of stops to arrest the carriage in selected column positions, a second class of key controlled means coöperating with the second set of stops to arrest the carriage in selected decimal positions in the selected columns, and a set of keys each of which simultaneously actuates a stop coöperating means of each of said classes, said stops of the first set being non-engageable by the key controlled means of the second named class.

9. In a typewriting machine, the combination of a power-driven letter feeding carriage, carriage releasing means to permit the carriage to be thrown from one column position to another, a first set of stops adjustable on the carriage for arresting the carriage in predetermined column positions, a second set of stops adjustable on the carriage for arresting the carriage in selected decimal positions in the columns, a first class of key controlled means coöperating with the first set of stops to arrest the carriage in selected column positions, a second class of key controlled means coöperating with the second set of stops to arrest the carriage in selected decimal positions in the selected columns, and a set of keys each of which simultaneously actuates a stop coöperating means of each of said classes, the stops of both sets being carried by a rack fast to the carriage, and the stop of the first set being shaped to avoid contact with the key operated means of the second class.

10. In a typewriting machine, the combination of a power-driven letter feeding carriage, carriage releasing means to permit the carriage to be thrown from one column position to another, a column skip

ping and selecting mechanism comprising; a set of stops each mounted on the carriage in a predetermined column position and being of progressively increased length from the first 5 to the last column; a set of movable pawls or detent devices arranged side by side in the direction of the length of the said stops and being spaced each from the next a distance corresponding to the difference in 10 length of two successive stops, key operated means for selecting and moving one of said pawls or detent devices into the plane of movement of the stops on the carriage, so that when the carriage is released, the pawl 15 so moved will be struck by any stop on the carriage which is of sufficient length to reach said pawl, and will be passed by the stops of insufficient length, a movable support for said pawls, said support being moved whenever any pawl is struck by a carriage stop, and a universal stop connected to said movable support and adapted when actuated by the movement of the latter, to arrest the carriage. 20

11. In a typewriting machine, the combination of a power-driven letter feeding carriage, carriage releasing means to permit the carriage to be thrown from one column position to another, a column skipping and selecting mechanism comprising; a set of stops each mounted on the carriage in 25 a predetermined column position and being of progressively increased length from the first to the last column; a set of movable pawls or detent devices arranged side by side in the direction of the length of the 30 said stops, and being spaced each from the next a distance corresponding to the difference in length of two successive stops, key operated means for selecting and moving one of said pawls or detent devices into the 35 plane of movement of the stops on the carriage, so that when the carriage is released the pawl so moved will be struck by any stop on the carriage which is of sufficient length to reach said pawl, and will be passed by the stops of insufficient length, a pivoted support for said pawls, said support being moved whenever any pawl is struck by a carriage stop, and a 40 pawl is struck by a carriage stop, and a universal spring controlled slide connected to said movable support and adapted when actuated by the movement of the latter, to arrest the carriage. 45

12. In a typewriting machine, the combination of a power-driven letter feeding carriage, carriage releasing means to permit the carriage to be thrown from one column position to another, a column skipping and selecting mechanism comprising; a set of stops each mounted on the carriage in a predetermined column position and being of 50 progressively increased length from the first to the last column; a set of movable pawls or detent devices arranged side by side in the direction of the length of the said stops, and being spaced each from the next a distance 55 corresponding to the difference in length of two successive stops, key operated means for 55 selecting and moving one of said pawls or detent devices into the plane of movement of the stops on the carriage, so that when the carriage is released the pawl so moved will be struck by any stop on the carriage. 60

length of two successive stops, key operated means for selecting and moving one of said pawls or detent devices into the plane of movement of the stops on the carriage, so that when the carriage is released the pawl 70 so moved will be struck by any stop on the carriage which is of sufficient length to reach said pawl, and will be passed by the stops of insufficient length, a movable support for said pawls, said support being moved whenever any pawl is struck by a carriage stop, and a universal stop connected to said movable support and adapted when actuated by the movement of the latter, to arrest the carriage. 75

13. In a typewriting machine, the combination of a power-driven letter feeding carriage, carriage releasing means to permit the carriage to be thrown from one column position to another, a column skipping and selecting mechanism comprising; a set of stops each mounted on the carriage in a predetermined column position and being of progressively increased length from the first to the last column; a set of movable pawls or detent devices arranged side by side in the direction of the length of the said stops, and being spaced each from the next a distance corresponding to the difference in length of two successive stops, key operated means for selecting and moving one of said pawls or detent devices into the plane of movement of the stops on the carriage, so that when the carriage is released the pawl so moved will be struck by any stop on the carriage which is of sufficient length to reach said pawl, and will be passed by the stops of insufficient length, a pivoted support for said pawls, said support being moved whenever any pawl is struck by a carriage stop, and a 90 pawl is struck by a carriage stop, and a universal spring controlled slide connected to said movable support and adapted when actuated by the movement of the latter, to arrest the carriage. 95

14. In a typewriting machine, the combination of a power-driven letter feeding carriage, carriage releasing means to permit the carriage to be thrown from one column position to another, a column skipping and selecting mechanism comprising; a set of stops each mounted on the carriage in a predetermined column position and being of progressively increased length from the first to the last column; a set of movable pawls or 100 detent devices arranged side by side in the direction of the length of the said stops, and being spaced each from the next a distance corresponding to the difference in length of two successive stops, key operated means for 105 selecting and moving one of said pawls or detent devices into the plane of movement of the stops on the carriage, so that when the carriage is released the pawl so moved will be struck by any stop on the carriage. 110

- which is of sufficient length to reach said pawl, and will be passed by the stops of insufficient length, a movable support for said pawls, said support being moved whenever any pawl is struck by a carriage stop, and a universal stop connected to said movable support and adapted when actuated by the movement of the latter, to intercept the path of movement of the carriage stop which struck the pawl so as to be struck by said carriage stop to arrest the carriage.
15. In a typewriting machine, the combination of a power-driven letter feeding carriage, carriage releasing means to permit the carriage to be thrown from one column position to another, a universal stop controlled from any one of a number of keys to arrest the carriage at different selected column positions determined by the selected key, a series of decimal stops operated from the same keys, and settable counter-stops adapted to determine whether the column-selecting means shall be effective.
16. In a typewriting machine, the combination of a power-driven letter feeding carriage, carriage releasing means to permit the carriage to be thrown from one column to another, a stop which is engaged and actuated by the carriage to arrest the carriage, and means extending in a horizontal plane co-operating with key controlled means working vertically for controlling the time of operation of the stop by the carriage, to arrest the carriage at selected positions.
17. In a typewriting machine, the combination of a power-driven letter feeding carriage, carriage releasing means to permit the carriage to be thrown from one column position to another, a stop movable into and out of engagement with the carriage, means whereby the movement of the carriage may be transmitted to said stop to cause the same to engage and arrest the carriage in different key controlled positions, stops extending horizontally from the carriage and key operated stops moving vertically to co-operate with and control said carriage operated stop.
18. In a typewriting machine, the combination of a power-driven letter feeding carriage, carriage releasing means to permit the carriage to be thrown from one column position to another, a stop movable into and out of engagement with the carriage, and key controlled means movable vertically into and out of the path of movement of horizontally extending members on the carriage, so as to be engaged and actuated by the members on the carriage after a predetermined movement of the latter; the movement of the carriage being transmitted by said key controlled means to said stop to move the latter into engagement with the carriage, thereby arresting the carriage.
19. In a typewriting machine, the combination of a power-driven letter feeding carriage, carriage releasing means to permit the carriage to be thrown from one column position to another, a stop bar, a key operating said carriage release and said stop bar, an extension on said bar, a stop on the carriage, a co-operating stop, and means controlled by said extension to position said co-operating stop to intercept the stop on the carriage.
20. In a typewriting machine, the combination of a power-driven letter feeding carriage, carriage releasing means to permit the carriage to be thrown from one column position to another, a series of stops on the carriage, a series of keys individual to said stops and controlling a co-operating stop operating member and the escapement release, and means independent of the length of throw of said co-operating member to selectively cause the co-operation of the stops on the carriage with said stop-operating member to arrest the carriage at a desired point.
21. In a typewriting machine, the combination of a power driven letter feeding carriage, carriage releasing means to permit the carriage to be thrown from one column position to another, a series of stops on the carriage carrying extensions, a series of pawls adapted to be each struck by a selected extension, a stop raised by each pawl to arrest the carriage, and keys controlling said pawls and escapement release.
22. In a typewriting machine, the combination of a power driven letter feeding carriage, carriage releasing means to permit the carriage to be thrown from one column position to another, a series of stops on the carriage, a series of pawls each co-operating selectively with a stop, a series of key operated members each controlling its pawl, and means operated by the pawls to arrest the carriage.
23. In a typewriting machine, the combination of a power driven letter feeding carriage, carriage releasing means to permit the carriage to be thrown from one column position to another, a stop movable on the frame, a pawl, a key setting said pawl, a member on the carriage to move said pawl when set, a rock shaft carrying said pawl, and an arm on said shaft engaging said movable stop to cause it to arrest the carriage.
24. In a typewriting machine, the combination of a power driven letter feeding carriage, carriage releasing means to permit the carriage to be thrown from one column position to another, a stop movable on the frame, a pawl, a carriage member arranged to strike said pawl, a rock shaft carrying said pawl, a rock arm extending from said shaft and engaging said stop to move it to arrest the carriage.
25. In a typewriting machine, the combination of a power driven letter feeding car-

riage, carriage releasing means to permit the carriage to be thrown from one column position to another, a stop movable on the frame, a carriage stop, a pawl, a rock shaft carrying said pawl, an arm on said rock shaft engaging the stop movable on the frame to cause it to move to intercept the carriage, and a key operated member adapted to raise said pawl into the path of said carriage stop to cause it to operate the said movable stop.

26. In a typewriting machine, the combination of a power driven letter feeding carriage, carriage releasing means to permit the carriage to be thrown from one column position to another, a stop movable on the frame, carriage stops, a rock arm, pawls on said rock arm arranged to selectively co-operate with said carriage stops, keys each moving a pawl to operative position, a rock shaft carrying said rock arm, and a second arm on said shaft engaging with said movable stop to move it to arrest the carriage when a pawl is moved by a carriage stop.

25 27. In a typewriting machine, the combination with a carriage, of a tabulating mechanism comprising a single set of stop keys, and interchangeable stops settable on the carriage, said stops comprising variously formed members for determining whether any key may be caused to arrest the carriage at a selected column, or at a selected decimal position in a column, the form of the stops also determining which key shall be co-operative with any given stop to arrest the carriage.

28. In a typewriting machine, the combination with a carriage, of a tabulating mechanism including variously formed stops on said carriage for causing the carriage to be selectively arrested at any of a plurality of columns, the column being determined by the form of the stop, other stops on said carriage for arresting it at denominational letter spaces, and a single set of keys operable to selectively determine by said first-named stops at what column said carriage shall be arrested, and additionally operable to determine by said other stops at what letter space in the column the carriage shall be arrested.

29. The combination with a carriage, of a tabulating mechanism comprising a single set of stop keys, means whereby each key may cause the arrest of the carriage either at its selected column or at a selected decimal position in a column, and members variously formed and settable on said carriage to selectively determine how said keys shall be effective, the form of said members determining which keys shall be co-operative therewith in arresting the carriage at a selected column position.

30. The combination with a set of key-actuated members, of both decimal stops

and column selecting devices ramifying from said members.

31. The combination with a carriage, of a tabulating mechanism including a rack, a series of column-stops adjustable thereon, a series of decimal stops to co-operate with said column stops, keys for operating said decimal stops, a series of column selecting tappets also mounted on said rack independently of said column stops, but out of the paths of said decimal stops, and column selecting mechanism moved from ineffective to effective position through or by said tappets.

32. The combination with a carriage, of a tabulating mechanism including a rack, a series of column stops adjustable thereon, a series of decimal stops to co-operate with said column stops, keys for operating said decimal stops, a series of column selecting tappets also mounted on said rack independently of said column stops, but out of the path of said decimal stops, and column selecting mechanism moved from ineffective to effective position through or by said tappets, said tappets forming a stepped series for co-operating with different column selecting devices.

33. The combination with a carriage, of a combined decimal-tabulating and column-selecting device including a set of keys, and both decimal-stop and column-selecting devices operated by said keys, column-stops to co-operate with said decimal-stop devices, and tappets adjustable independently of the column stops to co-operate with said column-selecting device to move a part thereof from ineffective to effective position.

34. The combination with a carriage, of a combined decimal-tabulating and column-selecting device including a set of keys, and both decimal-stop and column-selecting devices operated by said keys, column-stops on the carriage to co-operate with said decimal-stop devices, and tappets adjustable on the carriage independently of the said column stops to co-operate with said column-selecting device to move a part thereof from ineffective to effective position, said tappets being formed to pass freely by said decimal-stop devices.

35. The combination with a carriage, of a combined decimal-tabulating and column-selecting device including a set of keys, and both decimal-stop and column-selecting devices operated by said keys, column-stops to co-operate with said decimal-stop devices, and tappets to co-operate with said column-selecting device to move a part thereof from ineffective to effective position, the tappets and the column-stops being independently adjustable in the direction of the carriage.

36. The combination with a key, of a counter-stop and column-selector, both operated at each operation of said key, a col-

umn-stop to engage the counter-stop, and a tappet to coöperate with the column selector.

37. The combination with a key, of a counter-stop and column-selector, both operated at each operation of said key, a column-stop to engage the counter-stop, and a tappet to coöperate with the column selector, said tappet being constructed to pass freely

10 by said counter-stop.

38. A tabulating mechanism including a rod formed at its upper end with a decimal stop, and having a bent arm with a selecting finger thereon to control column-selecting

15 means.

39. The combination with a carriage, of a single set of keys, and both decimal-stop mechanism and column-selecting mechanism always moved to operative position by 20 said keys at the depression thereof, and means for arresting the carriage either by the decimal stop mechanism or column-selecting mechanism.

40. The combination with a set of keys, 25 of a set of selectors operable thereby, a set of interponents, a set of tappets, one for each selector, the tappets being of graduated lengths to engage the various interponents when the latter are set by the keys, and a 30 carriage arresting stop projected by any of said interponents when operated by its tappet.

41. The combination of a carriage rack, forked tappets thereon having arms extending 35 forwardly and of various lengths, a row of interponents extending forwardly and selectively movable into position for engagement with the different tappets, and a single stop moved by the tappets to effective position to stop the rack.

42. The combination with a carriage, of independently operable interponents, key-controlled devices for setting any interponent, tappets of various lengths to engage 45 the respective interponents, and means controllable by any interponent for arresting the carriage.

43. The combination with a carriage, of independently operable interponents, key-controlled devices for setting any interponent, tappets of various lengths to engage the respective interponents, means controllable by any interponent for arresting the carriage, and decimal stops also positioned 55 by said keys to engage column stops.

44. The combination of a carriage-arresting stop normally retired, a set of interponents, a set of tappets of varying lengths, a set of keys, means for enabling the keys to 60 set any of the interponents to position to be engaged by its corresponding tappet, and means for enabling any interponent when driven by its tappet to project said stop.

45. The combination of a carriage-arrest-

ing stop normally retired, a set of interponents, a set of tappets of varying lengths, a set of keys, means for enabling the keys to set any of the interponents to position to be engaged by its corresponding tappet, means for enabling any interponent when 70 driven by its tappet to project said stop, and a series of decimal carriage-arresting stops also operable by said keys.

46. The combination with a carriage, of a decimal-stop mechanism including keys, a 75 column-selecting mechanism controlled by the same keys, variously formed stops made effective by the run of said carriage for operating said column-selecting mechanism and stopping the carriage independently of said 80 decimal stops, and means to coöperate with the decimal stops to arrest the carriage.

47. The combination with a carriage and keys, of a carriage-releasing mechanism operable by said keys, both decimal stops and 85 column-selecting mechanism also operated by said keys, and variously formed stops arranged at intervals along the run of the carriage for coöoperating selectively with both the decimal-stop mechanism and the 90 column-selecting mechanism.

48. The combination with a carriage, of a set of carriage-driven devices, a graduated set of members to enable the carriage to drive said devices, and means operable by 95 any of said devices for projecting a stop to arrest the carriage.

49. The combination with a carriage, a set of keys, and both the decimal-stop and column-selecting mechanism always operated 100 by said keys to operative position, of variously formed means to coöperate with the carriage and settable thereon for determining whether it shall be arrested by the decimal-stop device or by the column-selecting 105 device.

50. The combination with a carriage and tabulating keys, of a column selecting and decimal stop mechanism operable by said keys, stops on the carriage to engage only 110 the decimal stops, other stops adjustable on the carriage independently of said first-named stops to engage only the column-selecting stop, and variously formed means settable on the carriage to determine which 115 shall be effective.

51. In a typewriting machine, the combination with a carriage, of column-selecting means, keys for controlling and setting said column-selecting means to be operatively 120 positioned by the carriage, and decimal stops positioned by the same keys.

52. The combination with a carriage, of a tabulating mechanism including normally ineffective column-selecting devices for causing the carriage to be arrested at any of a plurality of columns, decimal stop devices connected to said column-selecting devices,

and means on the carriage to cause the said decimal stop devices to arrest the carriage at other portions of its travel.

53. The combination with a carriage, of a set of keys, a universal stop, interponents selectively settable by said keys, and means on the carriage operable when the carriage reaches a column position corresponding to a set interponent, to actuate said interponent and through said interponent to project the universal stop, by means of power supplied by the moving carriage, to position to arrest the carriage.

54. The combination with a carriage and driving means therefor, of a set of keys, carriage-releasing means operable by each key to permit the carriage to be driven from one column position to another, a universal stop, interponents individual to said keys and selectively settable thereby, and a set of tappets arranged at column positions on the

carriage and each operable during the travel of the carriage to actuate a set interponent and thereby project said universal stop into position to arrest the carriage.

55. The combination with a carriage, of a set of tappets adjustable at letter-space intervals along the carriage and each having a different path of travel, a set of keys, a universal stop, interponents selectively settable by said keys into the path of corresponding tappets, and means common to said tappets and operated thereby, through power supplied from the carriage to project said universal stop when an interponent is engaged by a tappet, and arrest the carriage at a position determined by the position of said tappet.

GEORGE E. GRIFFIN.
